UNITED STATES PATENT OFFICE.

HENRY F. BECHMAN, OF BATTLECREEK, MICHIGAN, ASSIGNOR TO DUPLEX PRINTING PRESS COMPANY, OF BATTLECREEK, MICHIGAN.

PRINTING-PRESS.

SPECIFICATION forming part of Letters Patent No. 786,716, dated April 4, 1905.

Application filed July 22, 1904. Serial No. 217,704.

To all whom it may concern:

Be it known that I, HENRY F. BECHMAN, of Battlecreek, in the county of Calhoun and State of Michigan, have invented certain new and useful Improvements in Printing-Presses; and I hereby declare that the following is a full, clear, and exact description thereof, reference being had to the accompanying drawings, which form part of this specification.

This invention is an improvement in web-printing presses of the duplex type; and its object is to enlarge the capacity of such presses to enable them to print papers of larger size up to sixteen pages, although such press is capable of printing any even number of pages from two to sixteen.

The present invention is an improvement upon the well-known duplex flat-bed type-printing web-perfected press, and it mainly differs therefrom in the addition thereto of two additional beds and cylinders, which are above, parallel, and in vertical alinement with the lower beds of the ordinary duplex machine. In the drawings I have indicated the cylinders for the upper beds as mounted in independent carriers similar to those used for the lower cylinders and driven by pitman and cranks like the lower cylinders.

The principal advantages of this invention, however, are that I am enabled to use one feed mechanism, one delivery mechanism, and one equalizing or looping mechanism to handle any even number of pages from two to sixteen, thus enabling the ordinary mechanism of a duplex press to do double the work which it has heretofore been possible to do in that machine.

I will now describe the invention, with reference to the accompanying drawings, in which—

Figure 1 is a longitudinal sectional elevation or diagram of the complete machine, showing the mode of handling two webs therein to produce paper of more than eight pages—say a sixteen-page paper. Figs. 2, 3, 4, 5, 6, 7, and 8 are diagrammatical views illustrating different ways of threading the press printing in one color. Figs. 9, 10, and 11 are dia-

grammatical views illustrating the method of threading the web printing in multicolor. 50

In the drawings, A A' A² A³ designate the type-beds, which are shown arranged parallel one over the other in vertical alinement.

B, B', B², and B³ designate impression-cylinders which coact with the respective beds. 55 The cylinders B B' are journaled in carriers C, as in the ordinary duplex press, which carriers are reciprocated by means of pitman C' and crank-wheels C². The cylinders B² B³ are journaled in similar carriers c, which may be reciprocated by pitman c' from crank-wheels c², the crank-wheels C² and c² being driven by intermeshing gearing, as indicated in the drawings. On opposite sides of cylinder B are traveling guides b, and opposite cylinder B' and traveling therewith are guides b' and cylinders B² B³, having guides b² b³ traveling therewith, as shown. 60

D D designate the feed-in rolls, with which coact tapes D'.

E E are the delivery-rolls, with which coact tapes E'.

f f' are the lower and upper equalizers or web-looping rolls, which are mounted on reciprocating bars F, which are connected at 75 their lower ends by links f² to vibrating lever F', actuated by cam F².

The operation of the web feeding, delivery, and looping devices are substantially the same as that described in patent to Cox, No. 478,503, of July 2, 1892, and as in the ordinary duplex press and need no detailed explanation herein for that reason. Suitable stationary guides for the web are arranged in the frames at opposite ends of the beds, as 85 will be seen in the drawings and referred to in explaining the course of the webs through the machine.

As shown in Fig. 1, two webs are threaded through the machine. The outer or upper web W is led from the roll W' under a guide 1 to the feeding-rolls D, then is looped upward over the lower looper f, passes down under a guide 2, forward over the cylinder-guide b² between cylinder B² and bed A², back 95 to a guide 3, up over a guide 4, back over the

cylinder-guides b^3 , and between cylinder B^3 and bed A^3 , back to a guide 5, then looped under the upper looping-roller f' , and carried to the delivery E. So far as this web is concerned it is fed into and directed between the upper two beds and cylinders and looped and delivered exactly as the web is handled in the ordinary duplex press. The second or under web w is led from the roll w' , under guide 1, through the feed-in rolls D, being assembled there with the web W and fed simultaneously therewith, passes on as far as the looping-roller f , but instead of passing under the guide 2 is led downward to guide 6, opposite the cylinder B. It is then led inward between the cylinder B and bed A, passing over cylinder-guides b , then back to rear guide or coaxter roller 7, up over another guide 8, then back between the bed A' and cylinder B' , passing over the cylinder-guide rollers b' , back to a stationary guide 9, over which it is turned and carried back above the cylinder B' and below the bed A^2 to a guide 10 above the guide 8, and then passes up over guide 4 and above the cylinder B^3 direct to roller 5, where it is assembled with the web W once more and looped therewith under roller f' and passes therewith to the delivery-rolls E. So far as this particular web w is concerned it is fed into and through the two lower beds and cylinders and perfected thereby in substantially the same manner as the web is perfected in the ordinary duplex press. It will be observed, however, that I employ but one feeding-in mechanism, but one looping mechanism, and but one delivery mechanism to handle the webs and that the product of this press (both webs being threaded throughout in the manner described) would be sixteen pages printed in one color. Another method of threading this press is shown in Fig. 2, in which the webs W and w pass together as far as the roll 9, at which point they separate, web W then passing between cylinder B' and bed A' , around guide 8, directly up to and over guide 3, then back between bed A^2 and cylinder B^2 to guide 2, and then up to guide 5, where it meets the web w and passes therewith to the delivery. The web w is separated from web W at 9 and passes to the lower guide 6, then passes between lower cylinder B and bed A to guide 7, then up past web W to the upper guide 4, then between bed A^3 and cylinder B^3 to guide 5, where it meets web W and passes therewith to the delivery. In this press it will be observed that one web is perfected on the lower and top beds and the other web is perfected on the two intermediate beds.

Diagram Fig. 3 shows how one web may be perfected on the second and fourth beds. In this instance the web passes through the feed and from the lower looping-roller f direct to and around the guide 9, then between the bed A' and cylinder B' to the guide 8, then up to

the guide 4, back between the bed A^3 and cylinder B^3 to the guide 5, thence under the upper looping-roller f' to the delivery. In this way a single web may be perfected on the third and fourth bed.

Diagram Fig. 4 shows a web may be perfected on the top and bottom webs of this machine. In this instance the web passes from the roller f direct to the guide 6, thence between the bed A and cylinder B to the guide 7, thence up direct to the guide 4, back between the cylinder B^3 and bed A^3 to the guide 5, thence under the upper looping-roller f' to the delivery. In this instance the second and third beds and cylinders have no work to perform.

Diagram Fig. 5 shows how the web may be perfected on the first and third beds. In this instance the web passes over the lower looping-roller f to the guide 6, thence between bed A and cylinder B to the guide 7, then up over the guide 8, back between bed A^2 and cylinder B^2 to the guide 2, then up over the guide 5, down under the upper looping-roller f' , and thence to the delivery. In this instance the second and top beds and cylinders have no work to perform.

Diagram Fig. 6 shows how the web may be perfected on the two upper beds. In this case the web passes from the lower looping-roller f down under guide 2, then between bed A^2 and cylinder B^2 back to guide 3, up over guide 4, and back between bed A^3 and cylinder B^3 to guide 5, then down under the looping-roller and out to the delivery. In this instance the two lower beds and cylinders have no work to perform.

Diagram Fig. 7 shows how a single web may be perfected on the two lower beds. In this case the web passes from the lower looping-roller f down under guide 6, then between bed A and cylinder B to guide 7, then up over guide 8 back between cylinder B' and bed A' to guide 9, thence up past guide 2 to guide 5, thence down under the upper looping-roller f' to the delivery. In this instance the two upper beds and cylinders have no work to perform.

Diagram Fig. 8 shows how a web may be perfected on the two middle beds and cylinders, the web passing from lower looping-roller f down under guide 3, thence between bed A' and cylinder B' to guide 8, thence up over guide 3 back between bed A^2 and cylinder B^2 to guide 2, thence up over guide 5, down under the upper looping-roller f' to the delivery. In this case the top and bottom beds and cylinders have no work to perform.

Diagram Fig. 9 shows how a single web may be printed in colors on this machine. In this instance the web passes from roller f down under guide 3, then between bed A and cylinder B to guide 7, up over guide 8, back between bed A' and cylinder B' to and around guide 9, (being perfected on the two lower

beds and cylinders.) From guide 9 it passes back to and under guide 10 and then up over guide 3, back between bed A² and cylinder B² to guide 2, receiving a colored impression from bed A², and then passes from roller 2 up to guide 5, thence down under upper looping-roller f', and up to delivery. In this case the two lower beds may apply one color and the bed A² a different color to the web, or the bed A² may apply black perfecting color, the colored impression being taken from the forms on bed A'.

Fig. 10 shows another arrangement for printing a single web in multicolors on this machine. In this instance the web passes from looping-roller f' to and under guide 6, then between bed A and cylinder B to guide 7, up over guide 8, back between bed A' and cylinder B' to guide 9, back to guide 10, up over guide 4, back between bed A³ and cylinder B³ to guide 5, thence under upper looping-roller f' to the delivery. In this instance the web may be perfected on beds A A' and receive a colored impression on bed A³, or it may receive a colored impression on bed A' and a perfecting impression on bed A³. In this case the bed A² and cylinder B² have no work to perform.

Fig. 11 shows how a single web may be perfected in black and in colors on this machine. In this instance the web from the lower looping-roller f' passes down under roller 6, then between bed A and cylinder B to guide 7, up over guide 8, back between bed A' and cylinder B' to guide 9, then up over guide 2, between bed A² and cylinder B² to guide 3, up over guide 4, back between bed A³ and cylinder B³ to guide 5, down under upper looping-roller f', and thence to delivery. In this instance the web may receive perfected impressions in black from forms on beds A A' and perfected impressions in color from forms on beds A² A³, or it may receive impressions in color from forms on beds A A' and in black on beds A² A³, or it may receive impressions in black from forms on beds A A³ and in color from forms on beds A' A².

The foregoing examples simply illustrate the great capacity of the press and some of the numerous ways in which it may be utilized, and a few of the numerous threadings and manners in which the press may be threaded to produce different-sized papers in one or more colors, and I do not wish to restrict myself to any particular manner of threading the web in this press, but in every instance, it will be observed, whether the press is threaded to print small or large papers or to print in black or in multicolors, whether to print one or more webs, the web or webs are all handled by the same feeding, looping, and delivery mechanism, and this construction, whereby I am enabled to utilize a single feeding, looping, and delivery mechanism to handle one or more webs, printed in one or more colors in the

same machine, is a most important and useful feature of the invention. It will be noted, furthermore, that in this machine when printing a full-width web in colors the web has a direct "straight-line" lead through the press between the feed and delivery—that is, it does not have to be deflected from one side of the press to the other—and no angle-bars or turners or deflectors are required between the feed and delivery mechanisms in handling full-width webs during multicolor printing.

While I prefer the particular arrangement of beds shown and described in this machine, I do not wish to restrict myself thereto; neither do I wish to restrict myself to the precise number of printing-couples shown.

Having thus described my invention, what I claim as new, and desire to secure by Letters Patent, is—

1. In a flat-bed web-perfecting press, the combination with a single set of web feeding, looping and delivery mechanisms, of more than two printing-couples, and web-guiding devices whereby one or more webs may be printed, substantially as specified.

2. The combination in a printing-press of more than two printing-couples, each comprising a bed and coacting cylinder, arranged in alinement, of a single feed mechanism, a single delivery mechanism, a single looping mechanism, and suitable web-guides, whereby one or more webs may be directed between any or all of the printing-couples, substantially as described.

3. A printing-machine, comprising more than two printing-couples arranged parallel and in vertical alinement, and each comprising a bed and coacting cylinder; with a web-feeding mechanism, a web-delivery mechanism, and a web-looping mechanism intermediate the printing mechanisms and the feeding and delivery mechanisms, all adapted to handle one or more webs, through any one or all of the printing-couples, substantially as described.

4. In a printing-press, the combination of four type-beds and coacting cylinders, and web-guides beside the beds; with a single web-manipulating mechanism, comprising web-feed-in devices, web-feed-out devices and intermediate web-looping devices, whereby one or more webs may be directed between one or more of the printing-couples, substantially as described.

5. In a printing-press, the combination of four beds and four coacting cylinders arranged parallel and in vertical alinement, a single feed-in mechanism, a single web-delivery mechanism, and a single intermediate looping mechanism, all adapted to direct one or more webs between any one or all of the printing-couples, substantially as described.

6. The herein-described printing-press, comprising four stationary beds and four reciprocating cylinders coacting with the beds, stationary web-guides at opposite ends of the

beds, web-feed-in mechanism adapted to handle one or more webs, a web-delivery mechanism adapted to handle one or more webs, a web-looping device between the feed and the printing mechanism, and a web-looping device between the printing mechanism and the delivery, whereby one or more webs may be fed through the machine and imprinted on any one or more of the beds, substantially as specified.

7. A printing-machine, comprising more than two printing-couples arranged parallel and in vertical alinement, and each comprising a bed and coacting cylinder; with a web-feeding mechanism, a web-delivery mechanism, and a web-looping mechanism intermediate the printing mechanisms and the feeding and delivery mechanisms, whereby webs may be printed in colors, substantially as described.

8. The combination in a printing-press of more than two printing-couples, each comprising a bed and coacting cylinder, arranged in alinement, of a single web-feed-in mechanism, a single web-delivery mechanism, a single web-looping mechanism, and suitable web-guides whereby a web may be directed in a straight

line through the press and printed in colors by said couples, substantially as described.

9. In a printing-press, the combination of four type-beds and coacting cylinders, and 3 web-guides beside the beds; with a single web-feed-in mechanism, a single web-feed-out mechanism and intermediate web-looping devices, whereby a web may be directed in a straight line between the printing-couples and 3 printed in colors, substantially as described.

10. In a printing-press, the combination of four beds and four coacting cylinders arranged parallel and in vertical alinement, a single web-feed-in mechanism, a single web-delivery mechanism, and a single intermediate looping mechanism, and web-guides adapted and arranged to direct a web successively between the printing-couples to be printed in colors, substantially as described.

In testimony that I claim the foregoing as my own I affix my signature in presence of two witnesses.

HENRY F. BECHMAN.
